GRINDING DEVICE

George Pearson, Salt Lake City, Utah

Application November 11, 1929, Serial No. 406,391

2 Claims. (Cl. 51—170)

This invention relates to a grinding device, and more particularly to one which is electrically driven and is especially adapted to grinding the breaker points of the ignition system of an internal combustion engine, and has among its objects:

To construct a device of the kind specified which shall be simple and cheap to construct yet rapid and efficient in operation,

10 To invent a grinder which may be operated by current from the battery of an automotive vehicle or other circuit; or from a light circuit.

To prevent sparking at the change of the current from one coil to the other;

15 To construct a device of the kind named which will properly grind the said points to allow for the arcuate movement of one of them yet insure perfect contact;

To devise such a device which will permit of 20 its being held at an angle to the desired surface, yet will not form such surface with an improper relation to the rest of the point.

The satisfactory operation of an internal combustion engine depends to a great extent upon the 25 breaker points of the ignition system meeting with a full face to face contact, and the pitting of such points by the heat of the spark at each break makes it necessary that such points be ground frequently. When this grinding is done 30 by hand it requires either the removal of the points, or else takes a long time to do a job which may not be satisfactory when finished, due to the fact the faces formed on said points are not accurately in full contact over all their surfaces. 35 The present invention makes it possible to perform this operation rapidly and accurately.

Fig. 1 is a longitudinal sectional view of the assembly of this device;

Fig. 2 is a top plan view with the cap removed;

40 Fig. 3 is a plan view of a part of the magnetic circuit;

Fig. 4 is an elevational view of a bracket member;

Fig. 5 is a transverse section of the armature 45 on the line 5—5, Fig. 1;

Fig. 6 is an edge elevation of the abrasive element;

Fig. 7 is a cross section of the said element on the line 7—7, Fig. 1;

50 Fig. 8 is a diagram of the circuits in this device.

Coils 9 and 10, connected in series, are mounted on an insulating sleeve 11 with an iron shell 12 enclosing them, and an iron spacer 13 between their adjacent ends. An armature 14 is recipro- 55 cally mounted inside sleeve 11 upon a shaft 15,

said armature being spaced from said shaft and secured thereto by insulating members 16 which are set into the ends of said armature. Shell 12, spacer 13, and armature 14 are split, as shown at 17, 18, and 19, respectively, to prevent eddy currents. In the ends of shell 12 are iron members 20 and 21, split at 22 and 23 respectively, to serve as polepieces and form parts of the magnetic circuits. The aforementioned coils, spacer, and polepieces may be retained in shell 12 by 60 suitable fastening means, such as screw 24, or the said shell may be pressed thereon tightly enough to hold them in place.

A plate 25 of insulating material is secured to the outer face of polepiece 21, and on it are 70 mounted brackets 26 with upstanding ears 27 and 28, said ears having oppositely facing notches 29 and 30, respectively, cut therein. A yoke 31 is fixed to the upper end of shaft 15 by means of nut 32, said yoke being of non-conducting substance; holes 33 are formed through yoke 32, and through each of said holes is passed a spring 34, one end of each of said springs being attached to an ear 27 and the other end being attached to a vibrator 35. Secured on plate 25 by screw 75 36 is an insulating spacer 37 and on this is a metal support 38 which carries point 39, on said support is a second insulating spacer 40, on this is a second metal support 41 which carries point 42, and on this is an insulating washer 43. Points 39 and 42 are adapted to contact points 44 and 45 on vibrator 35. Wire 46 is connected to metal support 41 and to a source 47 of electric current, while wire 48 is connected to the other terminal of said source and to support 38; said vibrator 35 is also connected to the junction 49 of coils 80 9 and 10, by a wire 50.

The lower end of shaft 15 carries an abrasive element 51 which is fixed thereto by a flexible rubber coupling 52. This coupling comprises a 95 socket portion 52^a in which the end of the actuating shaft 15 is insertable, said socket portion enabling an easy connection and disconnection. The part 52^b is made to have the abrasive element fitted therein so as to be held during operation. 100 The mid-portion of diminished thickness imparts a desirable and necessary degree of flexibility, enabling the proper operation of the abrading element even though the tool may not be held perpendicular to the work. The foregoing element 51 is thicker at one side 53 than at the other side 54, said variation in thickness being such that said element is part of a sector of the circle which is described in part by the swing of the movable point of the breaker of the ignition sys- 105 110.

tem, so that the proper bevel will be imparted to the points of said breaker when said element 51 is placed therebetween with the edge 53 at the radially outer side of said points, with reference to the arcuate swing of said movable point. Coupling 52 is readily detachable from shaft 15 to permit the use of abrasive elements of different degrees of coarseness, and is flexible to allow shaft 15 to be held obliquely to the faces to be formed on the points being ground without making said faces also oblique to the desired plane of the faces.

Operation

16 Starting with the parts of the device in the positions shown in Figs. 1 and 8, for example, the element 51 is placed between the points to be ground, in the relation described above as to sides 53 and 54, the wires 46 and 48 being connected by means of clips to any exposed connections leading to the battery 47. Current will flow through wires 46 and 55, coil 9, wire 50, points 44 and 39, support 38, and wire 48 back to battery 47, energizing coil 9 and drawing armature 14 with the attached shaft 15 and element 51 upwardly; the resistance of wire 50, etc., being less than that of coil 10 the current will follow this path. At the upper limit of movement of shaft 15 the thrust of yoke 31 against springs 34 will draw vibrator 35 up, and the tension of said springs will snap point 45 into contact with point 42, thus closing the circuit through wire 46, points 42 and 45, wire 50, coil 10, and wire 56 back to battery 47, energizing coil 10, and drawing armature 14, shaft 15, and element 51 down, the yoke 31 and springs 34 acting to snap vibrator 35 down so that points 44 and 39 are again in contact.

35 It will be observed that at no time is there a breaking of the circuit, which would cause a destructively hot spark at such break and soon destroy points 39, 42, 44, and 45; when vibrator 35

is in such position that the points carried are not in contact with either of points 42 or 39 there is a closed circuit through wires 46, 55, coils 9 and 10, and wires 56 and 48, so that it is unnecessary to use a condenser to prevent the hot spark at break which would otherwise occur.

Edges 57 at the extremities of vibrator 35 are disposed in the notches 30 of ears 28 and so form a frictionless support for said vibrator, and thus shaft 15 can be rapidly oscillated by the changes in energization of coils 9 and 10, and the grinding of the breaker points be expeditiously effected by element 51 while said points are in place, thus saving the time and expense of removing them. Members 20 and 21, and spacer 13, act as pole-pieces to attract armature 14, and serve also to form a magnetic path of low reluctance between the ends of coils 9 and 10, in conjunction with shell 12. There is no change in the direction of flow of the lines of magnetic force, so that there is no energy consumed in sweeping out opposed residual magnetism in any part of the magnetic circuit.

20 The members 16, being of rubber, not only secure armature 14 upon shaft 15, but serve as resilient bumpers at the extremes of movement thereof, and their rebound starts the reverse movement of the said armature.

I claim:

1. A device for dressing breaker points, comprising a thin abrasive element, a reciprocable member, flexible means to connect said element to said member, and an electromagnetic means to reciprocate said member.

2. A device for dressing breaker points, comprising a thin abrasive element, a reciprocable member, a rubber connection between said element and said member, and an electromagnetic device to reciprocate said member.
